(57) **CLAIM**

The ornamental design for a disposable cup lid, as shown and described.

DESCRIPTION

This application relates to the following co-pending commonly owned patent applications: "Disposable Cup Lid," Ser. No. 29/275,940, and "Disposable Cup Lid," Ser. No. 29/275,937.

FIG. 1 is a rear perspective view of a disposable cup lid of our new design, that portion of the cup lid shown in phantom is not part of the claimed design and is provided for environmental purposes only.

FIG. 2 is a top plan view of the disposable cup lid, that portion of the cup lid shown in phantom is not part of the claimed design and is provided for environmental purposes only.

FIG. 3 is a bottom plan view of the disposable cup lid, that portion of the cup lid shown in phantom is not part of the claimed design sought and is provided for environmental purposes only.

FIG. 4 is a front side view of the disposable cup lid, that portion of the cup lid shown in phantom is not part of the claimed design and is provided for environmental purposes only.

FIG. 5 is a rear side view of the disposable cup lid, that portion of the cup lid shown in phantom is not part of the claimed design and is provided for environmental purposes only; and,

FIG. 6 is a side view of the disposable cup lid, that portion of the cup lid shown in phantom is not part of the claimed design and is provided for environmental purposes only.

The broken lines consisting of a long dash and a dot immediately adjacent to the shaded areas represent the bounds of the claim and form no part of the claimed design.
